Des. 217,544
Patented May 12, 1970

217,544

WIRE TRANSPORTER

Norman Green, 10106 Clark St.,
Philadelphia, Pa. 19116

Filed Oct. 24, 1968, Ser. No. 14,160

Term of patent 14 years

Int. Cl. D12—02

U.S. Cl. D14—3

Fig. 1

Fig. 2

Fig. 3

Fig. 4

FIG. 1 is a view in perspective of the front, top, and one side of the "wire transporter" embodying my new design;

FIG. 2 is a top plan view thereof;

FIG. 3 is a rear elevational view thereof; and

FIG. 4 is a side elevational view of the side opposite that shown in FIG. 1.

I claim:

The ornamental design for wire transporter, substantially as shown.
